UNITED STATES PATENT OFFICE.

EWALD C. GEHRKE AND EMIL A. GEHRKE, OF CHELAN, WASHINGTON.

COLD-WEATHER STARTER FOR MOTOR-DRIVEN VEHICLES.

1,419,840.

Specification of Letters Patent. Patented June 13, 1922.

Application filed July 29, 1921. Serial No. 488,411.

To all whom it may concern:

Be it known that we, EWALD C. GEHRKE and EMIL A. GEHRKE, citizens of the United States, and residents of Chelan, in the 5 county of Chelan and State of Washington, have invented a new and Improved Cold-Weather Starter for Motor-Driven Vehicles, of which the following is a description.

Our invention relates to means for priming the motor of a vehicle in cold weather, and has for its general object to provide 10 a device for the indicated purpose which will overcome the disadvantages of a primer dependent on engine suction for the feed of the priming fuel and at the same time will avoid the use of pump or like pressure device to cause a feed of the priming fuel. In starters requiring the choking of the mixing chamber in order to obtain the increased 15 suction, the choking reduces the air supply so that it is disproportionate to the volume of gasoline and fails to carry the gasoline in sufficient quantity to the intake manifold. We avoid the choking by delivering the 20 priming charge in the form of a spray or jet so that the atomized fuel may be the more readily carried to the intake manifold by the inflowing air, the lifting action required of the air being minimized when the priming charge is atomized.

Further objects of the invention are to avoid the necessity of pre-heating the priming charge and to provide a priming device which involves the minimum cost of manufacture and of a character to promote convenience in the emplacement of the device. 25

The above and other objects as will appear are attained by a primer having the novel features hereinafter particularly described and claimed.

Reference is to be had to the accompanying drawings forming a part of this specification, it being understood that the drawings are merely illustrative of one example 30 of the invention.

Figure 1 is a front elevation of our improved device showing the same in position;

Figure 2 is an enlarged partly sectional plan view of the device;

Figure 3 is a section on the line 3-3, Figure 2;

Figure 4 is a section on the line 4-4, Figure 2;

Figure 5 is a fragmentary sectional plan view of the device slightly modified.

In carrying out our invention in accordance with the illustrated example, we provide a valve having a casing 10 and a separate elongated plug 11 therein, the casing 60 being clamped between an annular shoulder or collar 12 on said plug near one end and a washer 13 pressed by a cap nut 14 screwing onto the plug 11 at the opposite end. The plug has an axial bore 15 and has 65 transverse ports 16 diametrically opposite leading radially outward from the bore 15 into the annular chamber 18 formed by the casing 10. A cylindrical strainer 17 is employed in practice surrounding the plug 11 70 and requiring the priming charge to pass through said strainer from the ports 16 to the chamber 18.

The casing 10 has a lateral outlet 19 at a side thereof which is internally threaded 75 to receive the threads 20 of a nipple 21 formed on an atomizer 22 from which the priming fuel is discharged. The atomizer 22 has in practice a flat form adapted to rest on the top of the carburetor A between the 80 same and the flange of the intake manifold B of a gasoline motor C, it being understood that the invention is applicable to any approved carburetor and motor. The atomizer 22 is formed with opposite edge flanges 23 85 having holes 24 for the stud bolts D that secure to the intake manifold B to the carburetor.

The valve plug 11 beyond the flange 12 presents a threaded terminal 25 in which a 90 coned axial inlet 26 leads to the axial bore 15 of the plug for the inlet of gasoline, said inlet constituting a seat for a needle valve 27, the stem 28 of which extends from said valve through the bore 15 and cap nut 14, 95 the rear end of the stem being formed with an eye 29 or other suitable means for the connection of an operating means 30, generally consisting of a wire extending to a point for convenient manipulation by the 100 chauffeur. A coil spring 32 surrounds the stem 28 between the eye 29 and the cap nut 14 and is secured to both in a manner tending to retract the valve stem after a pull

on the wire 30 and thereby tending to maintain the needle valve 27 to its seat closing the inlet to the axial bore 15 of the valve. The stem 28 within the plug 11 is of increased diameter as at 31 to thereby provide a secondary valve for closing the lateral outlet ports 16 in addition to the closing of the inlet 26 by the needle valve 27. Thus, the flow of fuel to the casing 10 is prevented even if the needle valve should not effect a tight closure of the inlet at 26. The threaded end 25 receives a cap nut 33 which serves to clamp to the valve one end of a length of hose 34 or other pipe connection, the opposite end of which is connected to a T-fitting 35 in the gasoline supply pipe E adjacent to the connection of said pipe with the float chamber of the carbureter A.

The atomizer 22 has fitted therein short lengths of copper tubing 36 which communicate at their outer ends with the bore 37 of the nipple 21. In the form shown in Figure 2 the tubes 36 have a longitudinal series of jet orifices 38 and said tubes follow the cylindrical wall of the central opening 39 formed in the atomizer to register with the mixing chamber of the carbureter and with the flanged neck of the intake manifold B.

In the form shown in Figure 5 the tubes 36^a communicate with the interior of the nipple 21 but instead of a longitudinal series of jet orifices, the terminal ends of the tubes are directed laterally inward toward the center of the opening 39 and formed in their extreme ends with jet orifices 38^a. The different forms of the tubes 36, 36^a adapt the device to a carbureter either of the type that is bolted horizontally or that provides for the bolting on of the carbureter vertically.

With a device constructed and arranged as described the hose or pipe 34 will be in constant communication through fitting 35 with the gasoline supply pipe E and upon the valves 27, 31 being moved to the open position by a pull on the wire 30, fuel will freely flow into the bore 15 and through the ports 16 to the casing 10 to pass out through the nipple 21 to the atomizing pipes 36 to the mixing chamber of the carbureter and to the intake manifold B. It will be observed that the opening of the valve is independent of the choking of the carbureter by operating the lever F of the choker rod G so that the normal air inlet of the carbureter is availed of during the priming. It will be observed also that there is no special provision required to be made for installing and supporting the attachment since the securing of the atomizer 22 positions the valve and the connection with the gasoline supply is permanently established by the connection of the hose 34 with the fitting 35.

We would state in conclusion that while the illustrated example constitutes a prac-

tical embodiment of our invention, we do not limit ourselves strictly to the mechanical details herein illustrated, since manifestly the same can be considerably varied without departure from the spirit of the invention as defined in the appended claims.

Having thus described our invention, we claim:

1. A priming device including a valve casing, an atomizer disposed in a plane transverse to said casing and adapted to be secured between an intake manifold and a carbureter to direct a priming charge to the fuel mixing chamber, said atomizer presenting an opening to register with the intake and carbureter and having members to be fastened with the fastening of the carbureter to the intake flange, said casing having a lateral outlet and the atomizer having a lateral inlet connected with said outlet to support the casing on the atomizer, a plug in said casing and formed with an axial bore having an inlet at one end leading thereto, and a lateral outlet between its ends leading therefrom, to the interior of the valve casing, a cap nut on the plug at the rear end, a valve stem axially movable in said plug and extending through the capped rear end thereof, said stem having valves thereon controlling respectively the inlet and the outlet of said plug, means to operate said valve stem, and means to connect the inlet end of the plug with a gasoline supply pipe.

2. A priming device including an atomizer presenting a central opening to register with an intake and carbureter and having means to secure the same between the intake flange and the carbureter, said atomizer having jet orifices at the opening thereof and having a lateral inlet, a valve casing connected with said inlet and supported thereby, a valve plug in said casing and formed with an axial bore, one end of which forms an inlet, said bore having outlets communicating with the interior of the valve casing, a valve stem movable axially in said plug, means to operate said valve stem, and means at the inlet end of the plug to connect the same with a gasoline supply pipe.

3. A priming device of the class described including an atomizer adapted to be secured between an intake manifold and a carbureter, and presenting an opening to register with both, said atomizer having an inlet and having jet orifices at said opening for the discharge of priming fuel to the mixing chamber formed by the carbureter and intake manifold, a valve casing supported by the atomizer and having an outlet communicating with the inlet of the atomizer, a plug extending through said casing and having a flange, a cap nut on the plug at the rear end and serving to clamp the valve casing between said nut and the flange of

the plug, said plug having a longitudinal throughbore, the bore at that end opposite the cap nut constituting an inlet, a stem movable axially in said bore and having a valve, to control said inlet, the end of the stem extending beyond the rear end of the plug and its cap for connection with an operating means, and a cap on the inlet end of the plug adapted to secure a hose there-to for connecting the valve with a gasoline supply pipe.
